DESIGN FOR A BOTTLE OR SIMILAR CONTAINER

John A. Oya, Honolulu, Territory of Hawaii

Application October 21, 1938, Serial No. 80,585

Term of patent 7 years

To all whom it may concern:

Be it known that I, John A. Oya, a citizen of the United States of America and a resident of Honolulu, T. H., have invented a new, original, and ornamental Design for a Bottle or Similar Container, of which the following is a specification, reference being had to the accompanying drawing, forming part thereof.

In the drawing, Figure 1 is a plan view of a bottle or similar container showing my new design, and Figure 2 is a front view of the same.

I claim:

The ornamental design for a bottle or similar container, as shown.

JOHN A. OYA.
